(57) **CLAIM**

The ornamental design for a clothing clip with a retaining socket, as shown and described.

DESCRIPTION

FIG. 1 is an isometric view of a clothing clip with a retaining socket according to the new design;

FIG. 2 is a front elevational view thereof;

FIG. 3 is a left side elevational view thereof, the right side view being an identical mirror image;

FIG. 4 is a rear elevational view thereof;

FIG. 5 is a top plan view thereof; and,

FIG. 6 is a bottom plan view thereof.

The broken line showing of a pair of eyeglasses in FIG. 1 is for illustrative purposes only and forms no part of the claimed design.
